Primary Examiner — Charles D Hanson*(74) Attorney, Agent, or Firm* — Cole Schotz, P.C.;
Marcella M. Bodner(57) **CLAIM**

The ornamental design for an asymmetric tissue graft, as shown and described.

DESCRIPTION

FIG. 1 is front elevational view of a first embodiment of an asymmetric tissue graft showing my new design;
FIG. 2 is a rear elevational view thereof;
FIG. 3 is a left side elevational view thereof;
FIG. 4 is right side elevational view thereof;
FIG. 5 is a top plan view thereof;
FIG. 6 is a bottom plan view thereof;
FIG. 7 is front elevational view of a second embodiment of an asymmetric tissue graft showing my new design;
FIG. 8 is a rear elevational view thereof;
FIG. 9 is a left side elevational view thereof;
FIG. 10 is right side elevational view thereof;
FIG. 11 is a top plan view thereof; and,
FIG. 12 is a bottom plan view thereof.
